UNITED STATES PATENT OFFICE.

ARTHUR D. WINSLOW, OF WILMETTE, ILLINOIS.

FLEXIBLE BUTTON.

Application filed June 16, 1924. Serial No. 720,261.

My invention relates to buttons, and more particularly to a button made of flexible material.

It is a purpose of my invention to provide a button that is made of flexible material so that the same will not be broken when the garment to which the same is attached is run through a wringer or similar member exerting pressure thereon.

It is a further purpose of the invention to provide a button that is made of resilient material, said button being reinforced so that the stitches for securing the same to the garment will not cut through the button.

It is still another purpose of the invention to provide a button of the above mentioned character which is made entirely of resilient material, said material being preferably of the same flexibility throughout, but said button being provided with a rib or raised portion adjacent the thread receiving openings therein for spacing the button from the material to which it is secured and for reinforcing the same adjacent the stitches.

More particularly it is a purpose of the invention to provide a button that has openings therein for receiving the stitches for securing the same to a garment with reinforcing means in the form of ribs or raised portions that extend from a point short of the peripheral edge portion of the button across the central portion thereof. Either a single rib or a plurality of ribs may be provided.

Other objects and advantages of the invention will appear as the description of the accompanying drawings proceeds. However, I desire to have it distinctly understood that I do not intend to limit myself to the exact details shown or described, but that I intend to include as part of my invention all such obvious changes and modifications of parts as would occur to a person skilled in this art and as would fall within the scope of the claims.

In the drawings:

Fig. 1 is a front face view of my improved button;

Fig. 2 is a transverse sectional view thereof;

Fig. 3 is a rear face view thereof; and

Fig. 4 is a rear face view of a slightly different construction of button.

Referring in detail to the drawings, in Figs. 1 to 3 inclusive is shown a button having a body portion 10 which is provided with openings 11 for receiving the stitches or threads for securing the button to a garment or other fabric member. The button is generally of the usual shape, being provided with a recessed portion 12 at the center thereof within which the openings 11 lie and with a thickened portion gradually increasing in thickness from the shoulder 13 outwardly to a point spaced from the extreme outer edge thereof as indicated at 14 from which point the surface of the button is curved convexly toward the outer edge thereof as indicated at 15, the rear face 16 of said button lying substantially in a plane and meeting the curved portion 15 of the front face thereof in a thinned edge portion 17. The rear face of the button is provided with a rib 18 which extends between the openings 11 and which terminates short of the peripheral edge 17 of said button, thus leaving a thinned edge around the entire periphery of the button, but providing reinforced openings 11 to prevent the cutting of the stitches or threads through the material of the button. The rib 18, it will be further noted, is thickest at the center 19 thereof and gradually decreases in thickness toward the ends thereof merging with the face 16 at the opposite ends of said rib 18. Thus the button has considerable flexibility throughout both halves thereof on opposite sides of the rib 18 and also adjacent the outer or peripheral edge portion 17 thereof in line with the rib 18, but provides a portion of considerable strength adjacent the stitches extending through the openings 11, it being obvious that the stitches or threads will extend across from one opening 11 to the other, crossing the rib 19.

The button is preferably made of rubber or other resilient material or compounds of rubber or other material providing a tough but resilient body that is of such flexibility that pressure thereon, such as exerted by a wringer or other device having rollers between which the garment may be passed in washing pressing or ironing the same, will not injure the same, but the button will flex or bend to take care of any distorting pressure exerted thereon. It is very desirable that the button be made of the same

kind of material throughout as any reinforcements or other inserts of other material will tend to break away from the rubber or resilient material when the body flexes, thus causing deterioration of the button when water or other liquid comes in contact with the reinforcement in the rubber.

By provision of the rib 18, the desired reinforcement is obtained without affecting the flexibility of the button or interfering with the operation thereof of passing the same through a button-hole as the peripheral edge is thin throughout the entire distance around the button and there is no thick part closely adjacent thereto. The rib further provides means for spacing the button from the material of the garment so that the same cannot be sewed too closely to the garment permitting the necessary tilting of the button relative to the garment and at the same time provides the reinforcement to prevent cutting by the thread of the button. When rubber is used for the button, the mixture and cure is such that the button has considerable flexibility and resiliency and will restore to its normal position, no matter how far it is bent out of shape without any injury to the button. Buttons of this character may be made of any desired color by inserting the proper pigment in the rubber mixture and need not necessarily be provided with any covering or coating of any kind in order to make the same of a desirable appearance.

In Fig. 4 is shown a slightly different form of button from that shown in Figs. 1 to 3 inclusive, the button in Fig. 4 comprising a body portion 10' which is the same shape as the body portion 10. The body portion 10' is provided with the openings 11' which are reinforced by the ribs 20. The ribs 20 may be made in the form of a cross or X and are made of the greatest thickness at the point of crossing 21 thereof and gradually decrease in thickness toward the ends 22 thereof.

Obviously, while two holes are shown in the button, any number may be provided, as it is obvious from Fig. 4 that the thick portion 21 may be used as well for four holes as for two and that if more holes are desirable, a different arrangement of ribs may be provided. The button in Fig. 4 is made of the same material as that shown in Figs. 1 to 3 inclusive and is made throughout of the same material just as is the button in Figs. 1 to 3. This button also has the peripheral edge portion 17' thereof, thin throughout the circumference thereof as the ribs 20 terminate short of the peripheral edge, leaving a thin edge portion between the ends thereof and the periphery of the button. If desired, the holes may be eliminated from the button of flexible material as the needle for stitching the buttons on

the material will readily pierce the flexible material.

Having thus described my invention, what I desire to claim and secure by United States Letters Patent is:

1. A button having a body portion of flexible material and a reinforcing rib of flexible material extending across the same and terminating short of the peripheral edge portion of said button.

2. A button of resilient flexible material comprising a body portion and a reinforcement, said button being made of the same material of substantially the same density throughout.

3. A button of flexible material comprising a body portion and a reinforcement, said button being made of the same material throughout, said body portion and said reinforcement being made integral of the same flexible material, said reinforcement being of the same density as said body portion.

4. A button of resilient flexible material comprising a body portion and an integral reinforcement projecting therefrom, said button being made of material of the same density and flexibility throughout.

5. A button having a body portion of resilient flexible material provided with openings and a reinforcement of resilient flexible material extending between said openings.

6. A button having a body portion of resilient flexible material provided with openings and an integral reinforcing rib of resilient flexible material extending between said openings.

7. A button having a body portion of resilient flexible material provided with openings and an integral reinforcing rib of resilient flexible material extending between said openings and terminating short of the peripheral edge portion of said button.

8. A button having a body portion of flexible material and a reinforcing rib of flexible material extending across the same and terminating short of the peripheral edge portion of said button, said rib gradually decreasing in height from the middle toward the ends thereof.

9. A button having a body portion of resilient flexible material provided with openings, and a thickened portion of resilient flexible material adjacent said openings on the rear side thereof providing a reinforcement for said button, said button having a thinned peripheral edge portion extending entirely around the same.

10. A button having a body portion of flexible material and a reinforcing rib of flexible material extending across the same and gradually decreasing in height from the middle toward the ends thereof.

In witness whereof, I hereunto subscribe my name this 10th day of June, A. D., 1924.

ARTHUR D. WINSLOW.
